UNITED STATES PATENT OFFICE.

RALPH BOWN, OF EAST ORANGE, NEW JERSEY, ASSIGNOR TO AMERICAN TELEPHONE AND TELEGRAPH COMPANY, A CORPORATION OF NEW YORK.

RADIO SIGNALING SYSTEM.

Application filed November 1, 1920. Serial No. 421,086.

To all whom it may concern:

Be it known that I, RALPH BOWN, residing at East Orange, in the county of Essex and State of New Jersey, have invented certain 5 Improvements in Radio Signaling Systems, of which the following is a specification.

This invention relates to radio signaling systems and especially to an arrangement whereby the wave lengths of the various 10 transmitting channels in a multiplex radio system may be controlled and interference thereby prevented.

In multiplex radio systems which are characterized by the operation of a plurality 15 of transmission channels under centralized control there arises the possibility of interference between the secondary stations, which are designed to operate with the various channels of the central station, unless special means are provided to avoid such interference.

This invention provides a method of operation which furnishes a positive way for securing the proper selection of frequencies 20 for the transmission channels between the transmitting and the receiving stations in a coordinated radio system. Although this invention is applicable to any system of radio transmission, it is especially designed 25 to facilitate the operation of a central multiplex radio station having a plurality of channels over which transmission may be maintained with a corresponding number of secondary radio stations. The arrangement 30 disclosed herein lends itself particularly well to the maintenance of radio telephonic communication between a multiplex shore station and a plurality of ship stations in a manner which will be more clearly described 35 hereinafter.

This invention will be better understood from the following description when read in connection with the attached drawing, of which Figure 1 represents diagrammatically 40 the circuit arrangements of a system comprising a central multiplex station and a secondary station; Fig. 2 represents the circuit arrangement of a system comprising two secondary stations which are designed 45 for intercommunication there-between; and Figs. 3 and 4 represent frequency scales intended to show an arrangement of the frequencies at the central and the secondary stations whereby interference between channels 50 is avoided.

In Fig. 1, A represents a primary station and B a secondary station which may be one of a plurality of similar stations adapted to maintain transmission with station A. At station A, a source of high frequency continuous oscillations 1 which may be of any well-known type, such as the well-known vacuum tube oscillator is connected with a modulator 2, with which is also connected a source of low frequency signals 3. The output side of the modulator is, in turn, connected with the amplifier 4, the output side of which is coupled with an antenna 5. The receiving circuit at the central station A comprises a balanced loop receiver 6, which 60 is so designed that it will not be affected by oscillations of the frequency transmitted from the antenna 5 of the transmitting circuit at station A. The balanced receiver will, however, respond to oscillations of a 65 predetermined frequency and will impress them upon a demodulator 7, with which is connected a local source of demodulating current 8. The local source of oscillations 8 is intended to impress upon the demodulator 70 oscillations of such frequency that, when beat with the oscillations of the received frequency, the resultant oscillations will lie within such a range of frequency as to pass through the band filter 9 and be impressed 75 upon the detector 10. The signal wave which is superimposed upon the received oscillations will be detected thereby.

The secondary station B comprises a transmitting and a receiving circuit, each 80 having its respective antenna but it is to be understood that the transmitting and receiving circuits may be so related as to operate in connection with a single antenna. In the arrangement disclosed, 11 represents 85 a source of high frequency oscillations, having associated therewith controlling means 12 for varying the frequency of the oscillation circuit. The output side of the oscillator is connected with a modulator 13, with which also is connected a source of low frequency signaling current 14. The modulated high frequency oscillations are amplified by an amplifier 15 and then impressed 90 upon the transmitting antenna 16. The receiving circuit comprises a receiving antenna 17, which is responsive to reception frequency and which is adapted to impress 95 the received oscillations upon a demodulator 18. The antenna 17 is also responsive 100 to the high frequency oscillations of the 105 oscillator 11. The demodulator 18 is connected with the detector 10, the output of which 110 is connected with the balanced receiver 6.

2
to oscillations transmitted by the antenna 16 of the transmitting circuit at station B. The oscillations of the frequency of 600,500 cycles (assuming that the device 21 produces oscillations of 500 cycles) received from the antenna 5 of the primary station, together with oscillations of the frequency of 570,000 cycles transmitted by the antenna 16, are beat together by the demodulator 18 and the resulting oscillations of 30,500 cycles, which is the proper range of frequency to pass through the band filter 19, will be impressed upon the detector 20. The resultant low frequency signal wave of 500 cycles will be perceived thereby.

Fig. 2 shows the relation existing when two similar secondary stations are transmitting between themselves. In this figure, parts which are similar to those shown in Fig. 1 have been given the same designating numerals. The stations represented by C and D may, for example, represent two ship stations which are attempting to establish communication between themselves. In this arrangement, the antenna 6' is not balanced against the transmitting antenna 5, and consequently it will respond to oscillations transmitted from the latter antenna, as well as from the oscillations from antenna 16 connected with the transmitting circuit of station D. And in a similar manner, the receiving antenna 17, associated with station D, will respond not only to oscillations transmitted by antenna 5, but also to oscillations transmitted by antenna 16.

No claim of inventorship is made by the applicant upon the circuit arrangements herein disclosed. These arrangements are substantially the same as those disclosed in the copending application of Farrington, Series No. 326,986, dated September 27, 1919. In the Farrington application there is disclosed and claimed means for utilizing a fractional part of the unmodulated carrier wave, which is transmitted from a secondary station to beat with the modulated frequency received at the same secondary station from the remote transmitting station and to obtain thereby a beat frequency, by means of which a signal from the remote station may be detected. It is the object of the applicant's invention to utilize the means disclosed in the Farrington application in carrying out a method whereby the frequency of transmission from secondary stations to a multiplex central station or between two secondary stations in communication with each other may be so controlled that interference between two or more secondary stations may be prevented.

Considering the arrangement shown in Fig. 1, let it be assumed that the station B desires to communicate with station A. The secondary station B would call station A, using therefor a standard calling wave

length and would be advised by station A as to the proper channel over which communication should be established. Let it be assumed that station A has three channels of communication represented, for example, by the frequencies of 600,000, 540,000 and 480,000 cycles respectively as shown in Figs. 3 and 4. As soon as the station A has advised the calling secondary station as to the proper channel of communication, it would begin to transmit oscillations of the frequency represented by the designated channel. The transmitted oscillations might either be modulated or unmodulated provided suitable signal indicating means are associated at the receiving end of the system, since the invention is not limiting to any special type of radiated signal. Modulated oscillations may be produced by operating the tuning fork 21 in front of the transmitter 3, associated with the low frequency signaling circuit and for the purpose of describing the invention, a system involving the use of modulated oscillations will be assumed. These modulated high frequency oscillations would be received by the receiving antenna 17 of station B. The antenna 17 will also receive oscillations which are generated by the oscillator 11, associated with the local transmitting circuit. The oscillations of the two frequencies are together passed into the demodulator 18, which produces the difference frequency of the two waves impressed upon the demodulator. In order that the resultant wave might be detected, the oscillations of the difference frequency must pass through the band filter or selective circuit 19. Thus, the difference in frequency between the standard transmitting wave of the primary station A and the transmitting wave of the secondary station B must lie within a certain range, in order that oscillations, whose frequency equals the difference between the frequencies of the two transmitting waves, may pass through the band filter and be detected by a suitable detecting device. It will be seen that the transmitting frequency of each channel of a primary station is fixed in accordance with a definite wave length schedule such as is shown in Figs. 3 and 4, and, likewise, the channels of the adjacent primary stations are similarly fixed, any secondary station must seek the proper assigned frequency for any particular channel of transmission, in order to establish communication over the channel assigned by the primary station with which it desires to communicate. That is to say, in order for station B to communicate with station A, the frequency of the oscillations radiated by the antenna 16 must be such that, when beat with the oscillations radiated from antenna 5, will produce a band of oscillations adapted to pass through the band filter 19. In other words, the band

filter 19, coupled with the controlled frequency transmitted from the primary station A over antenna 5, constitute means for controlling the frequency that the secondary station B must maintain, in order to communicate with the primary station A. It will be seen, therefore, that this method or system enables the primary stations to control the radiating frequency of the secondary stations and thereby prevents interference between the said secondary stations, which would result if such secondary stations were not given positive means to determine when their transmitting frequency was of the proper magnitude for maintaining transmission, without interfering with the transmission from neighboring secondary stations. For example, if the primary station A has assigned to the secondary station the use of channel No. 1, which, as will be seen by the scale of Fig. 3, has a frequency of 600,000 cycles, the operator at the secondary station will begin to raise (or lower) the frequency of his oscillator 11 until it approaches the desired magnitude, which is manifested by the detection of the signal in the output circuit of detector 20. The operator can, with a little practice, vary his transmitting frequency up and down the scale, so that the signal incoming from antenna 5 disappears by running alternately out one side and then the other, of the range of the band of the selective circuit 19 and he can adjust the difference frequency to the centre of this band and thereby insure that speech or other multi-frequency signals, which latter may be used in modulating the oscillations transmitted from the primary station A, will fall within the range of the selective circuit 19 and will not be distorted.

The method of controlling transmitting wave lengths in a multiplex radio system will be apparent from the diagrams shown in Figs. 3 and 4. Thus, Fig. 3 shows a desirable arrangement for the distribution of the channels associated with three primary stations A, A₁ and A₂ and nine secondary or ship stations and the frequencies of the said channels. Stations A, A₁ and A₂ each have three channels, which are assumed to be sufficiently widely separated geographically and the frequencies sufficiently widely separated electrically, as to be non-interfering among themselves. The channels of station A are numbered arbitrarily 1, 4 and 7, those of station A₁, 2, 5 and 8, and those of station A₂, 3, 6 and 9. The frequency of each channel may be determined by the scale at the left-hand side of the diagram. The ship stations have been given corresponding numbers primed. It will be seen from this diagram that if ship station 1' is operating over channel 1 with station A, and ship station 4' is operating over channel 4 with the same station, there

exists sufficiently wide separation between the frequencies of the two operating channels as to prevent interference there-between and, similarly, the ship stations are separated by frequency space of at least 10,000 cycles from the frequency range of the nearest channel transmitted from more remote primary stations than that with which the ship station may be operating, so that there is slight possibility of interference from this source. It will be seen, therefore, that by means of an arrangement such as has been disclosed herein, interference between the transmitting frequencies of neighboring stations in a multiplex system is substantially eliminated because, as soon as the operator at a secondary station brings his frequency up to the desired transmitting frequency, he will begin to receive oscillations through the band filter of his receiving circuit and thereby be apprised of the fact that his transmitting frequency is approaching its proper value. In other words, this system provides a definite transmitting frequency for each ship channel and means to indicate when such frequency is being transmitted.

It will be noted that, in describing the operation of the system in which this invention is embodied, reference has been made to the operation of a certain secondary station with a channel of a specific primary station. It is to be understood that any secondary station is capable of operating over a wide range of wave lengths, and consequently is adapted to maintain transmission over any channel of any primary station, selecting any assigned channel on the manner heretofore described.

The arrangement disclosed in Fig. 2 is, as stated, substantially the same as that shown in Fig. 1, station C corresponding to primary station A and station D to station B. In order to effect the proper operation of this arrangement, the oscillation frequency of the transmitting circuit of station C is held constant and the operator at secondary station D will operate to obtain the proper beat frequency in a similar manner as described in connection Fig. 1.

It is to be understood that, although this method has been described in connection with certain specific circuit arrangements, it is capable of being used in other and different arrangements, without departing from the spirit and scope of the appended claims.

What is claimed is:

1. In a multiplex radio system comprising primary and secondary stations, the method of controlling the transmitting frequency of a secondary station, which consists in transmitting from the primary station a modulated wave of fixed frequency, beating the received modulated wave at the said secondary station with the unmodulated trans-

mitted wave of the said secondary station and adjusting the frequency of the said unmodulated transmitted wave until the difference in frequency between the received 5 modulated wave and the unmodulated transmitted wave will be of such magnitude as to pass through a selective circuit associated with the receiving circuit of the said secondary station.

2. In a multiplex radio system comprising primary and secondary stations, the method of controlling the transmitting frequency of each secondary station, which consists in transmitting from the primary station a 15 modulated wave of fixed frequency, receiving the said modulated wave at the secondary station, generating at the secondary station an unmodulated transmitting wave and impressing a portion of the unmodulated 20 wave upon the secondary receiving circuit, together with the modulated received wave, varying the frequency of the unmodulated wave until the beat frequency of the two waves lies within the frequency range 25 of a selective circuit and impressing the said beat frequency upon detecting apparatus.

3. In a multiplex radio system comprising a plurality of primary and a plurality of 30 secondary stations, each of the said primary stations having a plurality of transmitting channels, a method of controlling the transmitting frequency of each secondary station, which consists in transmitting over each 35 channel of each primary station a modulated wave of fixed frequency, which differs from that of the neighboring channels by a definitely fixed amount, assigning each of said secondary stations to its respective 40 channel, generating an unmodulated transmitting wave at each secondary station and beating the said unmodulated wave with the modulated wave of the proper channel received by the said secondary station and 45 varying the frequency of the said unmodulated wave until a beat frequency is obtained that lies within the range of frequencies adapted to pass through a band filter associated with the detecting circuit of the said 50 secondary station.

4. In a multiplex radio system comprising primary and secondary stations, the method of controlling the transmitting frequency of each secondary station, which consists in 55 transmitting from the primary station a modulated wave of fixed frequency, beating the received modulated wave at the said secondary station with the unmodulated transmitted wave of the said secondary 60 station and adjusting the frequency of the said unmodulated transmitted wave until the difference in frequency between the received modulated wave and the unmodulated transmitted wave will be of such magnitude as to pass through a selective 65

circuit associated with the receiving circuit of the said secondary station.

5. In a multiplex radio system comprising primary and secondary stations, the method of controlling the transmitting frequency 70 of a secondary station, which consists in transmitting from the primary station a wave of fixed frequency, beating the received wave at the said secondary station with the transmitted wave of the said secondary station, and adjusting the frequency of the transmitted wave until the beat frequency will be of such magnitude as to pass through a selective circuit associated with the receiving circuit of the said 75 secondary station.

6. In a multiplex radio system comprising primary and secondary stations, the method of controlling the transmitting frequency of 80 a secondary station, which consists in transmitting from the primary station a wave of fixed frequency, receiving the said wave at the secondary station, generating at the secondary station a wave of different frequency and impressing the latter wave upon 85 the secondary receiving circuit, together with the wave received from said primary station, varying the frequency of the wave generated at said secondary station until the beat frequency of the two waves lies within 90 the range of a selective circuit, and impressing the resultant beat frequency upon 95 detecting apparatus.

7. In a multiplex radio system, comprising a plurality of primary and a plurality of 100 secondary stations, each of the said primary stations having a transmitting channel, the method of controlling the transmitting frequency of a secondary station, which consists in transmitting over the said channel of each primary station a modulated wave of fixed frequency, which differs from that of other channels by a definitely fixed amount, assigning each secondary station 105 to its respective channel, generating a transmitting wave at each secondary station, and beating the said transmitting wave with the wave of the proper channel transmitted from the primary station to the secondary station, varying the frequency of the said 110 generated wave until a beat frequency is obtained that lies within the range of frequencies 115 adapted to pass through a band filter associated with the detecting circuit of the said secondary station.

8. In a multiplex radio system comprising a plurality of primary and a plurality of secondary stations, each of the said primary stations having a transmitting channel, the method of controlling the transmitting frequency of each secondary station, which consists in transmitting over the said channel of a primary station a wave of 120 fixed frequency which differs from that of other channels by a definitely fixed amount, 125

- assigning each secondary station to its respective channel, generating at each secondary station a transmitting wave, demodulating the wave received from said primary 55
- 5 station by the wave generated at said secondary station, varying the frequency of the generated wave until the resultant beat frequency is of such magnitude as to pass through a selective circuit associated with 60
- 10 the detecting circuit of the receiving circuit.
9. In a radio system comprising primary and secondary transmitting channels, the method of controlling the transmitted frequency of secondary transmission channels, which consists in transmitting over a primary channel a wave of assigned frequency, transmitting a wave over a secondary channel, receiving both of said waves, causing 65
- 15 them by interaction to produce a third frequency characteristic of the said two transmitted waves, and adjusting the frequency of the said secondary transmitted wave so that the said third frequency shall have an 70
- 20 assigned value.
10. In a radio system comprising a plurality of primary and a plurality of secondary stations, each of the said primary and secondary stations having one or more transmitting channels, the method of controlling 75
- 25 the transmitting frequency of secondary stations which consists in assigning pairs, each composed of a primary transmitting channel and a secondary transmitting channel forming a two-way communication channel, transmitting over a primary channel a modulated wave of fixed frequency, transmitting a wave over the corresponding secondary channel, beating the 80
- 30 two waves together in the receiving apparatus of the secondary station and adjusting the frequency of the secondary transmitting wave until the said beat frequency lies within the range of frequencies adapted 85
- 35 to pass through a selective circuit associated with the secondary station.
11. In a radio system comprising a plurality of stations, the method of controlling from one station the transmitting frequency 90
- 40 of a second station, which consists in transmitting from the first station a modulated wave of fixed frequency, beating the received modulated wave at the said second station with the unmodulated transmitted wave of the said second station and adjusting the frequency of the said unmodulated transmitted wave until the difference in frequency between the received modulated wave and the unmodulated transmitted wave will be of such magnitude as to pass through a selective circuit associated with the receiving circuit of the said second station. 95
- 45
12. In a radio system comprising a plurality of stations, the method of controlling from the first station the transmitting frequency of a second station, which consists in transmitting from the first station a modulated wave of fixed frequency, receiving the 60
- 50 said modulated wave at the second station, generating at the second station an unmodulated transmitting wave and impressing a portion of the unmodulated wave upon the receiving circuit of the said second station together with the modulated received wave, varying the frequency of the unmodulated wave until the beat frequency of the two waves lies within the frequency range of a selective circuit, and impressing the beat frequency upon detecting apparatus. 80
- 55
13. In a radio system comprising a plurality of stations, the method of controlling from one of said stations the transmitting frequency from a second station, which consists in transmitting a modulated wave from the said first station, generating and transmitting an unmodulated wave from the said second station, impressing waves of both frequencies upon the receiving circuits at 90
- 60 each station and varying the frequency of the wave generated and transmitted from the said second station until the beat frequency between the waves received at both stations will lie within a range that may be passed through the receiving circuit and detected. 95
- 65
- 50
- In testimony whereof, I have signed my name to this specification this 30th day of October, 1920.

RALPH BOWN.
